UNITED STATES PATENT OFFICE.

JOHN L. SARDY AND CHARLES N. COLES, OF NEW YORK, N. Y.

THERMOMETER.

SPECIFICATION forming part of Letters Patent No. 332,947, dated December 22, 1885.

Application filed June 2, 1885. Serial No. 167,425. (No model.)

To all whom it may concern:

Be it known that we, JOHN L. SARDY and CHARLES N. COLES, residing at New York, in the county and State of New York, have 5 invented certain new and useful Improvements in Thermometers, of which the following is a specification.

Our invention relates more particularly to the scale-plate and casing or frame of the thermometer, and aims at compactness and durability of construction, and contemplates producing a cheaper article of manufacture than any now on the market.

Our invention consists in constructing the 15 aforesaid scale-plate and frame of a single piece of metal, and forming integrally therewith the top, bottom, and side flanges in such a manner as that they will afford complete protection to the tube and bulb.

20 Our invention also provides a slit in the face of the scale-plate and frame, through which the position of the sensitive fluid within the tube may be observed, the said tube being placed in the rear of this plate and contiguous 25 to the slit. The thermometer-tube, though attached to the rear of the scale plate, is so arranged as that it will protrude beyond the exposed surface of said plate, so as to permit the light's having an easier access to the same. 30 The tube is attached to the frame by suitable wire rings, and the whole construction is of such a nature that they can be made very cheap, and easily and quickly assembled.

Referring to the accompanying drawings, 35 Figure 1 represents a face view of our invention. Fig. 2 is a side view looking from the rear. Fig. 3 is a cross-section on the line $x-x$, Fig. 1. Fig. 4 is a cross-section on the line $y-y$.

A represents the scale-plate, having the side 40 flanges, A' , and the top and bottom flange, a . These parts, taken together, constitute the frame or casing of the thermometer, they being stamped and cut from a single piece of metal, and are consequently integrally formed, 45 as will be described. The top and bottom flanges, a , are provided with openings O for the purpose of ventilating the interior of the casing. The upper opening, O , is also utilized as a means for suspending the instrument 50 on the wall, the hook or nail being inserted in

it. This arrangement presents an additional advantage, in view of the fact that we contemplate, besides lithographing or printing the scale upon the face of the casing, of utilizing it by the same process for advertisement purposes, and the dispensing with the hole in the said face will secure for such means an uninterrupted space in the upper part of the instrument. The tube T is set against the frame from the rear, and it finds a seating in the hollow receptacles stamped up from the body of the scale-plate or face. The detail view in Fig. 3 represents the respective positions of the parts in this respect. The bulb T' is slightly bent from the alignment of the tube proper, 60 and in such a manner that it will not be in contact with the rear surface of the casing. The position of the mercury or other sensitive fluid is observed through the slit, and the tube is so arranged that by virtue of the offsets or receptacles B the said tube projects beyond the surface of the scale-plate, and is thus the more easily read, being more exposed to the light. 70

The tube is secured to the frame by means of rings D , which encircle the tube and are 75 threaded through openings in the plate. We may also apply a protecting-shield and a reflecting-surface, E , on the back of the tube T .

Having thus described our invention, what we claim as new therein, and desire to secure 80 by Letters Patent, is—

1. A thermometer-case formed of a single piece of metal, and having the top, bottom, and side flanges turned back from the face or scale-plate, in combination with the tube fastened in the rear of the said plate, as shown 85 and described, and for the purpose set forth.

2. In combination with the thermometer-casing, formed of a single piece of metal provided with a longitudinal opening, as described, the tube fastened to the rear of the scale-plate and projecting through the opening, as set forth. 90

3. The thermometer-casing, formed substantially as described, and having a slit or longitudinal opening in the face thereof, in combination with the tube attached to the casing, contiguous to and directly behind the slit, whereby the tube and its bulb are thoroughly 95 protected and the readings easily made. 100

4. The thermometer-casing A, having the flanges A' and a, the offsets or receptacles B, and the slit or opening C, with the thermometer-tube T and attaching-rings D, as set forth and shown.

5. In combination with the casing A, having the longitudinal opening C, the thermometer-tube T, projecting through the opening,

and the attaching-rings D, the shield or guard E, for the purposes described.

JOHN L. SARDY.
CHARLES N. COLES.
